INVENTOR
C. T. MC CORMICK

BY *E. E. Hesemann*
ATTORNEY

UNITED STATES PATENT OFFICE.

CYRUS T. McCORMICK, OF FREDERICKTOWN, MISSOURI.

COMBINATION TOOL.

Application filed June 10, 1922. Serial No. 567,415.

To all whom it may concern:

Be it known that I, CYRUS T. McCORMICK, a citizen of the United States of America, residing at the city of Fredericktown, 5 county of Madison, State of Missouri, United States of America, have invented a certain new and useful Combination Tool, of which the following is such a full, clear, and exact description as will enable anyone 10 skilled in the art to which it appertains to make and use the same, reference being had to the accompanying drawings, forming part of this specification.

My invention relates to a combination tool 15 and more particularly to a tool which may be used either as an expansion bit or an adjustable washer cutter.

One object of my invention is to provide the tool with such a form of pilot bit that 20 the said bit will operate effectively in connection with either of the forms of cutting tool used. Another object of my invention is to provide an improved form of boring cutter for use when the device is operated 25 as an expansion bit.

In the accompanying drawings which illustrate one form of device made in accordance with my invention, Figure 1 is a side elevation showing the device as an expansion bit, Fig. 2 is a section taken on the line 2-2 of Fig. 1, Fig. 3 is an end view of the cutting tool shown in Figs. 1 and 2, Fig. 4 is an enlarged section taken on the line 4-4 of Fig. 6, Fig. 5 is a bottom plan view of 30 the device as used as a washer cutter, and Fig. 6 is a side view of the lower part of the device used as a washer cutter.

10 indicates the body of the cutter holder, which body is preferably cylindrical in form 40 and provided with a transverse slot 11 adapted to receive the cutting tool. The cutting tool is held in the slot 11 by means of a threaded stud 12 adapted to bear against the upper edge of the cutting tool and carried by a cylindrical member 13 terminating in a square tapered shank 14 adapted to be held in an ordinary carpenter's brace.

The cutting tool which is used to adapt the device as an expansion bit consists of an 45 adjustable bar 15 and a cutting blade 16 ar-

ranged at right angles thereto and preferably formed integral therewith. This cutting blade 16 is U-shaped in cross-section, as best shown in Fig. 2, and each side terminates in a cutting lip 17 which lips are slightly diverging, as best shown in Fig. 1, so as to provide the proper clearance for the tool. One side of the cutting blade 16, preferably the inner side, is extended rearwardly and turned over to form a routing cutter 18 55 arranged between and behind the cutting lips 17.

In order to adapt the device as an adjustable washer cutter, the bar 15 is replaced by a pair of bars 19 each provided with a downwardly projecting blade 20. This form of cutting tool is not in itself novel and I claim the same only in combination with the other parts of my device.

In order that the tool may work equally 70 well as an expansion bit and a washer cutter, I provide a pilot bit 21, the body of which is cylindrical and slightly tapered in form and which terminates in a nonthreaded cutting point 22. This point is preferably 75 produced by forming three flat surfaces on the end of the pilot bit is illustrated. Such a form of point will cut but will not draw the pilot bit into the material at a uniform rate as the ordinary form of threaded pilot bit 80 will. In order to dispose of the chips formed by the cutting point 22, I provide the tapered body 21 of the pilot bit with grooves 23 which grooves however are so arranged as not to produce cutting edges.

The operation of my device will be evident. When the bar 15 is secured in position by means of the stud 12, the device is used as an expansion bit and the amount of feed may be regulated by the pressure on the 85 device so as to accommodate the cutting to different sizes of holes which could not be accomplished if the pilot bit were provided with a threaded point, as the feed would then be uniform and could not be varied to 90 accommodate the size of the hole bored. Furthermore the tapered form of the body of the bit holds the tool firmly in line while the hole is being bored. These features are 95 of equal importance when the device is used 100

as an adjustable washer cutter by the substitution of the two bars 19 for the bar 15.

It will be seen therefore that with my form of pilot bit the device works equally well as an expansion bit or washer cutter.

Having fully described my invention, what I claim as new and desire to secure by Letters Patent of the United States is:

A cutter for extension bits comprising an

adjustable bar, and a boring blade carried thereby, said boring blade being U-shaped, the lower end of each side of said blade forming a lip, and one side of said blade being bent over to form a routing cutter arranged between and behind said lips.

In testimony whereof, I have hereunto set my hand and affixed my seal.

CYRUS T. McCORMICK. [L.S.]
